SUBSTATION TELEPHONE CIRCUITS

Filed March 2, 1921

—Inventor—
Talbot G. Martin

Char. In. Candy Atty:

UNITED STATES PATENT OFFICE.

TALBOT G. MARTIN, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

SUBSTATION TELEPHONE CIRCUITS.

Application filed March 2, 1921. Serial No. 449,604.

The present invention relates in general to substation telephone circuits, but more especially to substation telephone circuits for automatic telephone systems, and the principal object of the invention is to provide a circuit arrangement for a desk telephone which permits the use of an automatic calling device with the standard Bell talking circuit, while requiring a minimum number of conductors in the cord connecting the telephone proper with the bell box.

It is well known that good practice requires some special provision to be made for preventing interference between the talking circuit and the switch control, or impulse transmitting circuit, controlled by the calling device. For instance, it has always been considered necessary to provide means for preventing clicks or objectionable noises in the receiver due to interruptions in the line circuit when the calling device is operated, and it is also desirable to shunt the transmitter while the calling device is being operated because its variable resistance is apt to produce an inferior quality of impulses. Considerable thought has been expended by inventors in accomplishing these results. In the patent to Willis, #1,313,570, granted August 19, 1919, reissued March 22, 1921, No. 15,070, there is shown a desk telephone circuit of the type referred to herein in which a calling device is provided with a single pair of shunt springs which are effective to bridge the calling device impulse springs directly across the line when the calling device is operated, thus removing the transmitter from the line, or impulsive circuit, and shunting the local receiver circuit so that the receiver will remain quiet. Since these shunt springs connect the calling device across the line, however, an extra conductor in the cord is required to connect with the line side of the primary induction coil winding, the induction coil being located in the bell box where the line terminates. Now, it has been found by experiment that the primary induction coil winding may well be left in the impulse transmitting circuit in series with the calling device impulse springs, as its effect is inappreciable; and it is possible, therefore, to eliminate one of the cord conductors provided that suitable circuit arrangements are provided for separately

shunting the transmitter and receiver with- 55 in the telephone instrument itself.

More specifically, then, the present invention may be considered to be an improvement on the circuit shown in the Willis patent, differing therefrom essentially in 60 that the primary winding of the induction coil is included in the impulse transmitting circuit, and in that an additional contact is provided in the shunt spring assembly, with shunt circuits adapted to separately shunt 65 the transmitter and receiver whenever the calling device is operated.

The improved substation circuits will now be described with reference to the accompanying drawings, in which Fig. 1 is a 70 wiring diagram of an automatic desk telephone and bell box, while Fig. 2 is a simplified circuit diagram.

Referring first to Fig. 2, the talking circuit as before stated is of the well known 75 Bell common battery type. With the receiver removed from the hook the transmitter T and the winding 4 of the induction coil are bridged across the two line wires 2 and 3, while the receiver R is in series with the winding 5 of the induction coil and the condenser C is connected in shunt of the transmitter. The transmitter and receiver circuits are both normally open and are closed in the usual manner by the switch-hook H when the receiver is taken off the hook. Contact springs 6 and 7 are included in the receiver circuit, while contact springs 8 and 9 are included in the transmitter circuit. 85 90

For receiving incoming signals the ringer M is provided, which is normally bridged across the line independent of control by the switch-hook. It will be observed that the ringer bridge includes a condenser, and 95 that this condenser is the same one which is associated with the receiver R, this condenser being common to the ringer bridge and to the local receiver circuit.

Associated with the lower side of the line 100 is a subscriber's impulse sender, or calling device, which is indicated by the reference character S. This sender may be of the type which is shown and described on pages 34 and 35 of "Automatic Telephony" by 105 Smith and Campbell, published by the McGraw-Hill Book Company. It comprises essentially a pair of impulse springs 15 and

16 which are controlled by a cam (not shown) through the medium of a finger hold dial (also not shown), and three shunt springs 12, 13, and 14, together with suitable 5 means for retaining these springs in the position shown in the drawing when the calling device is not in use, and for placing all three springs in engagement with each other when the calling device dial is turned from 10 its normal position. The impulse springs 15 and 16 are connected in series with the lower line wire 2 and their function is to produce momentary interruptions of the line circuit for the purpose of operating the central 15 office switches. The function of the shunt springs 12, 13 and 14 is to short circuit or shunt the transmitter T and the receiver R while the calling device is being operated to transmit impulses. To accomplish this one 20 spring is connected to the junction of the receiver and transmitter, while the other two springs are connected to the opposite sides of the transmitter and receiver, respectively, and it will be evident that with the 25 springs connected in this manner when they are brought into engagement the transmitter and receiver will both be short circuited, as stated.

In Fig. 1 the circuits have been drawn out 30 in detail, similar parts being indicated by the same reference numerals. For convenience in avoiding crosses in the conductors, some of the contact springs have been rearranged, particularly the calling device 35 springs and the switch-hook springs, but the circuit is precisely the same and it is believed that the change in the positioning of the springs will cause no confusion. The apparatus at the right of the drawing, comprising 40 the transmitter T, the receiver R, the switch-hook H, and the calling device S, constitutes the desk telephone proper; while the apparatus at the left of the drawing, and comprising the ringer M, the condenser C, 45 and the induction coil I, is separate from the telephone and in accordance with the usual practice is mounted in the so-called bell box. The telephone is provided with the terminal strip P in the base thereof, and the bell box is 50 provided with the terminal strip P'. The various circuits are completed by means of a cord which connects the two terminal strips, which it will be observed comprises only four conductors. The line extending to the 55 exchange is connected to the terminal strip P' in the manner clearly shown in the drawings.

The operation of the substation circuits is 60 as follows: When the receiver is removed to initiate a call the switchhook contact springs 7 and 9 come into engagement, respectively, with the contacts 6 and 8, whereby the transmitter T is bridged across the line in series with the primary winding of 65 the induction coil, and the receiver R is con-

nected in shunt of the transmitter in series with the secondary winding of the induction coil and the condenser. Responsive to the closure of the transmitter bridge, current is supplied to the transmitter from a bridged 70 battery at the central office (not shown) over the following path: line conductor 3, winding 4 of the induction coil I, transmitter T, contact springs 8 and 9 and impulse springs 15 and 16 to the line conductor 2. The bridge at the central office, which includes the battery, may also in accordance with the usual practice include the controlling relay of an automatic switch, the circuit of said relay including, therefore, the transmitter 80 bridge at the telephone. It follows that the calling subscriber by suitably manipulating his calling device dial may produce a series of interruptions in the circuit of the controlling relay to bring about the operation of 85 the switch.

It should be noted in this connection that as soon as the dial is turned from its normal position the substation loop is completed over a path which may be traced from the line conductor 3 by way of winding 4 of the induction coil, shunt springs 12, 13 and 14, switch-hook contact springs 8 and 9, and the impulse springs 15 and 16 to the line conductor 2. It will thus be seen that the variable resistance of the transmitter is excluded from the switch control, or impulse transmitting circuit, during the entire time that the calling device is in operation and is included again in the bridge across the line only when the calling device dial returns to its normal position. At the same time that the transmitter is short circuited the receiver R is also short circuited by means of the shunt springs 12 and 13. The purpose of 105 this for one thing is to prevent the currents induced in the secondary winding from producing clicks or noises in the receiver. Although this may be considered to be the primary purpose of short circuiting the receiver 110 during impulses, or at least the most obvious one, there is another advantage secured in that the high impedance receiver winding is excluded from the local circuit of the secondary winding. The secondary winding of 115 the induction coil is thus practically short circuited and the impedance of the primary winding is thus greatly reduced.

Succeeding operations of the calling device will now result in the operation of individual automatic switches at the exchange until the connection is finally completed to the line of the called subscriber, it being understood that all of the switches are provided with controlling relay bridges which, 125 with the exception of the bridge in the last switch, are successively cut off from the line after their associated switches are operated.

The connection having been completed, conversation may be held as desired, the 130

5 talking circuits functioning the same as usual in such cases. When the receiver is replaced at the end of the conversation, the transmitter and receiver circuits are broken at the switch-hook contacts and further flow of direct current through the substation 10 from the exchange is prevented. As a result all the switches at the central office are released and restored to normal in the usual 15 manner. The substation is now in condition to receive incoming signalling currents which may come in over the line conductors 2 and 3 and pass through the ringer M and the condenser C, whereby the ringer is actuated to advise the subscriber that he is being called.

It will be seen from the foregoing that I have devised an especially advantageous circuit for an automatic desk telephone which 20 possesses all the desirable features of former circuits and which makes it possible to use a cord comprising only four conductors for connecting the telephone itself with the bell box.

25 Having described my invention, what I consider to be new and desire to have protected by Letters Patent will be pointed out in the appended claims.

What I claim as my invention is:

30 1. In a substation telephone set, a line circuit, an induction coil, a transmitter and one winding of said induction coil in a bridge of said line, contact springs for closing the said bridge, a shunt circuit for said transmitter including a condenser, a second winding of said induction coil, and a receiver, a second set of contact springs in the shunt circuit between the receiver and the 35 said second coil winding, a subscriber's impulse sender for transmitting current impulses over the line circuit, shunt springs and means for actuating them when the impulse sender is operated, a shunt circuit controlled by said shunt springs for directly short-circuiting the said transmitter, and another shunt circuit controlled by said shunt springs for directly short-circuiting 40 said receiver.

45 2. In a substation telephone set, a line circuit, an induction coil, a transmitter and one winding of said induction coil in a normally open bridge of the line, a local circuit connecting opposite terminals of said transmitter and including a condenser, a second 50 winding of said induction coil, and a receiver, said local circuit being normally open, said receiver and transmitter normally connected together, means for closing said bridge and local circuit, a subscriber's impulse sender for transmitting current impulses over the line circuit, shunt springs and means for actuating them when the impulse sender is operated, and shunt circuits 55 controlled by said shunt springs for short-circuiting the said transmitter and receiver,

said shunt circuits including three conductors, one extending to the normally connected terminals of the transmitter and receiver, and the other two extending to the other terminals of the transmitter and receiver, respectively.

3. In a substation telephone set, an induction coil, a transmitter and a circuit therefor including one winding of said induction coil, a receiver and a circuit therefor including a condenser, a second winding of said induction coil, and the said transmitter, a normally open connection in the conductor common to said circuits, a second normally open connection between the receiver and said second winding, means for closing said connections, a subscriber's impulse sender at the substation, shunt springs and means for actuating them when the impulse sender is operated, and shunt circuits excluding any normally open contacts controlled by said shunt springs for directly short circuiting the said transmitter and receiver, said shunt springs being ineffective for closing said normally open connections.

4. In a substation telephone set, a line circuit, an induction coil, a transmitter in bridge of said line, a condenser, a winding of said induction coil, and a receiver in a second bridge of said line, a conductor common to said bridges and including a second winding of said induction coil, a normally open connection in each bridge outside of the common conductor, means for closing said connections, a subscriber's impulse sender, shunt springs and means for actuating them when the impulse sender is operated, and shunt circuits controlled by said shunt springs for short circuiting the said transmitter and receiver by connecting the four terminals thereof directly together.

5. In a substation telephone set, a line circuit, an induction coil, a transmitter in bridge of said line, a condenser, a winding of said induction coil, and a receiver in a second bridge of said line, a conductor common to said bridges and including a second winding of said induction coil, a normally open connection in each bridge outside of the common conductor, means for closing said connections, a subscriber's impulse sender, three shunt springs in said sender so connected that upon the operation of said sender both the transmitter and receiver are short circuited whether the receiver is off the hook or not, a terminal strip providing for the line connections and all connections of said condenser and induction coil, a second terminal strip providing for all connections of the remaining apparatus, and a four conductor cord joining said terminal strips over which all necessary circuits are completed as set forth.

6. In a substation telephone set, a line circuit, an induction coil, a transmitter and

the primary winding of said induction coil in a bridge of the line, a receiver, a local circuit for said receiver including said transmitter, a condenser, and the secondary winding of said induction coil, one terminal of said receiver being permanently connected to the junction of the transmitter and the primary winding of the induction coil, contact springs for closing the transmitter bridge, other contact springs for closing the receiver circuit, an impulse sender including a pair of impulse springs in series with one line conductor, shunt springs in said sender actuated when the same is in operation, and a shunt circuit controlled by said shunt springs for directly short circuiting said transmitter whereby the transmitter but not the said primary winding is excluded from the said bridge during the transmission of impulses.

7. In a substation telephone set, a line circuit, an induction coil, a transmitter and the primary winding of said induction coil in a bridge of the line, a receiver, a local circuit for said receiver including said transmitter, a condenser, and the secondary winding of said induction coil, one terminal of said receiver being permanently connected to the junction of the transmitter and the primary winding of the induction coil, contact springs for closing the transmitter bridge, other contact springs for closing the receiver circuit, an impulse sender including a pair of impulse springs in series with one line conductor, shunt springs in said sender actuated when the same is in operation, a shunt circuit controlled by said shunt springs for directly short circuiting said transmitter

whereby the transmitter but not the said primary winding is excluded from the said bridge during the transmission of impulses, and a second shunt circuit controlled by said shunt springs for directly short circuiting said receiver, whereby the receiver is prevented from responding to currents induced in the secondary winding.

8. In a substation telephone set, a line circuit including a calling device, a transmitter and one winding of an induction coil in series, a local circuit including a receiver, a condenser and another winding of the induction coil in shunt of the transmitter, and shunt springs controlled by the calling device for permanently closing a shunt circuit for the other winding including this condenser while the calling device is being operated.

9. In a substation telephone circuit, a line circuit, a calling device, a transmitter and one winding of an induction coil in series with the line circuit, a shunt circuit around the transmitter and also in series with the calling device in the line circuit including a receiver, a condenser and another winding of the induction coil, shunt springs controlled by the calling device for directly short circuiting the transmitter and receiver and thereby closing a short circuit around the second winding of the induction coil and the condenser, said shunt circuits all in series with the calling device in the line circuit.

In witness whereof, I hereunto subscribe my name this 19th day of February, A. D., 1921.

TALBOT G. MARTIN.
